UNITED STATES PATENT OFFICE

168,600

SEPARABLE FISH-SCALING CLAMP OR
SIMILAR ARTICLE

Clarence Seeber, Toledo, Ohio

Application April 17, 1952, Serial No. 19,376

Term of patent 14 years

(Cl. D44—29)

To all whom it may concern:

Be it known that I, Clarence Seeber, a citizen of the United States of America, residing at Toledo, in the county of Lucas, State of Ohio, have invented a new, original, and ornamental Design for a Separable Fish-Scaling Clamp or Similar Article, of which the following is a specification, reference being had to the accompanying drawings, forming a part thereof.

The figure is an isometric elevational view of the separable fish-scaling clamp, shown in my new design.

I claim:

The ornamental design for a separable fish-scaling clamp or similar article, as shown.

CLARENCE SEEBER.
